ATTORNEY

Patented Nov. 24, 1925.

UNITED STATES PATENT OFFICE.

ALBERT H. STEBBINS, OF LOS ANGELES, CALIFORNIA.

CONCENTRATING UNIT.

Application filed March 9, 1923. Serial No. 623,890.

To all whom it may concern:

Be it known that I, ALBERT H. STEBBINS, a citizen of the United States, residing at Los Angeles, in the county of Los Angeles, and State of California, have invented an Improvement in Concentrating Units, of which the following description, in connection with the accompanying drawings, is a specification, like characters on the drawings 10 representing like parts.

This invention relates to a separating unit, and more particularly to an installation for passing air through several concentrator tables.

15 Concentrator tables are extensively used for the separation of ores and other materials in accordance with their differences in specific gravity, and two different types of concentrator tables are now in general 20 use, one type is known as the wet concentrator table and the other type is known as the dry concentrator table. In the wet type water is used to promote separation of the materials, and in the dry type air is forced 25 through the materials to promote separation thereof.

The present invention relates to mechanism for supplying air under pressure to a plurality of dry concentrator tables, and to 30 mechanism for conducting from the tables the air which has passed through the material being treated.

One important feature of the present invention resides in a construction by which 35 air under pressure is supplied to several concentrator tables from a common source of air pressure, such as a fan.

Another feature of the invention resides 40 in a construction whereby air that is supplied to different concentrator tables is conducted from each of the tables to a common suction means, and the air being conducted from the concentrator tables may be passed through one or more dust extractors to remove 45 the dust.

Other features of the invention and novel 50 combination of parts in addition to the above will be hereinafter described in connection with the accompanying drawings which illustrate one good practical form thereof.

In the drawings:

Fig. 1 is a front elevation of a group of concentrator tables, and shows conduit means for conducting air to and from the 55 tables.

Fig. 2, on an enlarged scale, is a rear elevation of two of the concentrator tables of Fig. 1, the air supply conduits being shown in section. 60

Fig. 3 is a side view of one of the concentrator tables of Fig. 2; and

Fig. 4 is a plan view of a portion of a deck surface for one of the tables.

The present invention is applicable to any 65 type of concentrator table in which air is used in separating materials, and the concentrator tables 10 of the drawings may be regarded as any conventional type of dry concentrator tables. The tables 10 may be 70 arranged side by side as shown, or they may be distributed about a building to meet the requirements of various working conditions.

Each concentrator table 10 may consist of 75 a supporting frame 11 upon which is mounted a deck 12. These decks are usually supported at a lateral inclination as shown to impart a lateral movement to the materials being treated, and the decks usually are in the form of relatively long closed receptacles 80 having a deck surface 13 mounted between the upper and lower faces of the deck.

The materials to be treated may be delivered to the deck surface 13 by a hopper 85 14 at one end of the deck, and travel of the materials along the deck surface is commonly obtained by vibrating the deck back and forth in the general direction of its length.

The deck surface 13 is commonly provided with inclined riffles 15, and apertures 16 formed in the deck surface permit compressed air below the deck surface to pass 90 upwardly through the apertures and through the materials upon the deck surface. 95

In the concentrator table construction shown air is delivered to the deck at one end thereof and below the deck surface 13 by a wide hood 17, and the cover for the deck is shown as having a cone shaped portion 18 from which a conduit 19 leads. The construction is such that air under pressure is delivered to the deck below the deck surface by the hood 17, and the air which passes 100 upwardly through the apertures 16 and accumulates above the deck surface is carried off by the conduit 19.

As above pointed out the present invention is applicable to any preferred or well known type of concentrator table employing air as a separating medium, and it is therefore believed to be unnecessary to de- 110

scribe herein in detail a particular type of concentrator table.

The present invention contemplates that each of the tables 10 be supplied with air from a common source of supply, and to this end air under pressure is supplied by a fan 20 and may be led therefrom by a main conduit 21 toward the different tables 10 to be supplied. Branch conduits 22 leading from the main conduit 21 to each of the tables 10 are provided, and the main conduit 21 preferably is installed below the floor 23 of the building as shown so that it will be out of the way of persons attending the concentrator tables installed upon this floor. The size of the main conduit 21 preferably is reduced as shown in the direction in which air passes therethrough, and in proportion to the number of branch conduits leading therefrom, thereby to maintain the pressure in the conduit substantially constant by reducing the area of the conduit as the volume of air passing therethrough is reduced by the branch conduits.

Since the table decks are usually vibrated back and forth during the treatment of materials, a flexible connection 24 serves to connect the upper end of each branch conduit 22 with the lower end of a hood 17 leading into a deck. The amount of air supplied to each deck may be controlled by providing each branch conduit with an adjustable valve or gate 25.

From the construction so far described it will be seen that each concentrator table 10 receives its supply of air from the fan 20, that the main conduit leading from the fan toward the concentrator table may be mounted below the floor 23 where it will be out of the way, and that the supply of air to each concentrator table may be controlled as desired by the valves or gates 25.

In most table concentrators it is desirable to provide suction means for removing the dust laden air that accumulates above the deck surface 13, and the present invention contemplates a construction in which a single suction means may serve to remove air from a number of different concentrator decks. It may also be desirable to provide means for extracting dust from the air drawn off from the different concentrator tables.

In the construction shown, a suction fan 26 is provided to exhaust air from the space above the deck surface 13 of each concentrator table, and a suction dust collector 27 is interposed between the fan 26 and the concentrator tables 10. The dust collector 27 may be similar in construction to that disclosed and claimed in my Patent No. 1,509,910, filed April 13, 1922, and conduits 19 above mentioned may lead from each concentrator deck 12 to an auxiliary drum 28 of the dust collector 27. This will permit

the heavier dust to settle in the drum 28 before the air passes into the main portion 29 of the dust collector for further treatment. A conduit 30 leads from the dust collector 27 to the fan 26 and serves to draw the dust laden air from the different concentrator tables.

The dust collector 27 will remove a large portion of the dust from the air before it reaches the fan 26, and if desired, dust may be further removed from the air by passing the air through one or more dust removing devices after it leaves the fan 26.

In the present construction air discharged from the blast side of the fan 26 passes through a conduit 31 to a blast dust collector 32, and after leaving the dust collector 32 it may pass through a conduit 33 to a different type of dust collector 34 for final treatment. The dust collectors 32 and 34 if desired may be similar to the dust collectors disclosed and claimed in my applications, Serial No. 553,120, filed April 15, 1922, and Serial No. 565,199, filed June 1, 1922.

As a result of the present construction a single suction fan may serve to remove dust laden air from a number of concentrator tables and may serve also to pass the dust laden air through one or more dust removing devices. The amount of suction produced within each deck may be controlled as desired by providing a valve or gate 35 within each conduit 19.

What is claimed is:

1. A concentrator unit comprising in combination, a series of concentrator tables each having an enclosed deck, a deck surface therein, and an air chamber below the deck surface; means for supplying air under pressure to each deck from a common source, comprising a fan and conduits for conducting air under pressure from the fan to each deck; and means for removing the dust laden air from the different decks comprising an exhaust dust collector, an auxiliary dust collector connected to the exhaust dust collector between the latter and the decks to form a container adapted to receive the discharge ends of the different conduits and to provide a settling chamber, separate branch conduits leading from each deck to the auxiliary dust collector, and a suction fan for sucking the dust laden air from the different decks successively through the conduits, auxiliary dust collector and suction dust collector.

2. A concentrator unit comprising in combination, a series of concentrator tables mounted on the same floor of a building and each having an enclosed deck, a deck surface therein, means for supplying operating air to each deck from a single source comprising a fan, a main air conduit leading from the fan and located below said floor out of the way, separate branch conduits

extending upwardly from the main conduit to each deck to supply air under pressure to the decks; and means for removing the dust laden air from the different decks comprising an exhaust dust collector, an auxiliary dust collector connected to the exhaust dust collector between the latter and the decks to form a container adapted to receive the discharge ends of the different conduits and to provide a settling chamber, separate

branch conduits leading from each deck to the auxiliary dust collector, and a suction fan for sucking the dust laden air from the different decks successively through the conduits, auxiliary dust collector and suction 15 dust collector.

In testimony whereof, I have signed my name to this specification.

ALBERT H. STEBBINS.
